UNITED STATES PATENT OFFICE.

ROBERT T. BELL AND CHARLES H. VEITE, OF CINCINNATI, OHIO.

MECHANICAL MOVEMENT.

SPECIFICATION forming part of Letters Patent No. 795,189, dated July 18, 1905.

Application filed February 27, 1905. Serial No. 247,421.

To all whom it may concern:

Be it known that we, ROBERT T. BELL and CHARLES H. VEITE, citizens of the United States, residing at Cincinnati, in the county of 5 Hamilton and State of Ohio, have invented certain new and useful Improvements in Mechanical Movements, of which the following is a specification.

Our invention relates to improvements for 10 producing reciprocatory motion of a member simultaneously revolving about an axis disposed at an angle to the line of such reciprocatory motion.

The object of our invention is to provide a 15 machine of this character of the simplest possible construction.

Our invention consists of a shaft journalized in a suitable frame and having an endless spiral groove or track and a longitudinal groove or track, a block mounted on the shaft to slide lengthwise thereof, a pin mounted within the block adapted to be engaged by the spiral track, a gear housed in the block adapted to be turned with the shaft by the 25 longitudinal track or to slide lengthwise of the shaft with the block, an additional shaft mounted in the block at an angle to its line of motion, a member mounted on the additional shaft adapted to be rotated by the gear housed 30 in the block; and means for preventing the block from turning with the shaft.

Our invention also consists in the parts and combination and arrangement of parts as herein described.

35 In the drawings, Figure 1 is a side elevation of our invention connected by a chuck to a flexible shaft, a portion of which is shown. Fig. 2 is a plan of Fig. 1, excepting that a portion of the frame is broken away. Fig. 3 40 is a section on the line *v v* of Fig. 2. Fig. 4 is a section on the line *w w* of Fig. 2. Fig. 5 is a section on the line *x x* of Fig. 2. Fig. 6 is a longitudinal section of the block on the line *y y* of Fig. 2 and also showing a portion 45 of the grooved shaft, the pin, and retaining-screw and a portion of the guide-rod in elevation. Fig. 7 is a longitudinal section of the block and portions of the angularly-disposed members on the line *z z*, Fig. 1, also showing 50 a portion of the grooved shaft and pin and portions of the angularly-disposed shafts in

elevation. Fig. 8 is a perspective view of the pin. Fig. 9 is an elevation of one of the angularly-disposed members. Fig. 10 is an elevation of one of the angularly-disposed shafts. 55

The construction of our invention is as follows, reference being had to the drawings:

The frame 1, preferably constructed so as to form a convenient handle for the entire machine, has the shaft 2 journaled in the bearings 3 and 4 near its ends. The bearing 3 is preferably a removable one, while the bearing 4 may be adjusted to take up the wear of the shaft 2, so as to effectively prevent "end play" of the latter. Also mounted in the 60 frame 1 parallel with the shaft 2 is the guide-rod 5. Mounted to slide on the shaft 2 and the guide 5 are the blocks 6 and 7. These blocks are recessed to form housings for the double bevel-gears 8 and 9, respectively. The 65 shaft 2 has a longitudinal groove or keyway 10, and the bevel-gears 8 and 9 have feathers projecting into the groove 10, so that the bevel-gears are compelled to revolve with the shaft and may also slide longitudinally thereof with 70 the blocks 6 and 7. To produce the reciprocatory motion of the blocks, the shaft 2 is provided with endless spiral grooves 11 and 12, and the pins 13 and 14 are housed in the blocks 75 6 and 7, respectively, so as to bear in the endless spiral grooves 11 and 12, respectively. These grooves are so disposed on the shaft 2 that the blocks will move in opposite directions relative to each other. They are represented in the drawings in their positions 80 nearest to each other—that is, when the pins 13 and 14 are at the adjacent reversing-points of their respective grooves.

The pin 13 or 14 is composed of the cylindrical portion 15 and widened portion 16. 90 The block 6 or 7 is provided with a recess 17 to receive the widened portion 16 of the pin and a smaller opening 18 to receive the cylindrical portion 15 of the pin, whereby a pivotal bearing is formed for the pin in the 95 block. The recess 17 extends far enough upward into the block to permit the pin to be raised above the opening provided for the grooved shaft 2. After the grooved shaft 2 has been inserted through the openings provided for it and through the bevel-gears 8 and 9 the pins 13 and 14 may drop into their 100

grooves in the shaft. The smaller opening 18 is threaded to receive a screw 19, which is adapted to bear on the upper end of the pin 13 or 14 and hold it in the spiral groove.

- 5 Each block 6 or 7 is provided with the studs 20, which form shafts for the members 21 at right angles to the grooved shaft 2. The ends of the members 21 are provided with bevel-gears meshing with the bevel-gears 8 and 9, slidably mounted on the grooved shaft 2. Upon these members are mounted the cylinders 22, of any suitable material. Preferably the studs 20 are braced by the yokes 23 near their outer ends.
- 15 The operation of the machine is as follows: The shaft 2 is rotated by a convenient means, such as the flexible shaft here shown, whereupon the blocks 6 and 7 will be made to traverse the shaft by the spiral grooves. The 20 pin 13 or 14 being oblong in cross-section where it bears in the grooves will not change its direction at the crossing-places 24 of the grooves, but only at the final turning-point 25, therefore the blocks will continuously and 25 with uniform speed reciprocate and carry the bevel-gears 8 and 9 with them; but at the same time these bevel-gears will be rotated because of their feathered connection with the shaft 2 and will rotate the members 21 30 and the cylinders mounted thereon by means of the bevel-gears. These cylinders, it is obvious, will be caused to rotate in opposite directions, so that their effect upon the movement of the machine as a whole will be *nil*.
- 35 Likewise the movements of the blocks 6 and 7 are opposite, so that they will not disturb the equilibrium of the machine. Obviously these features would be necessary in a portable machine such as the one here illustrated, 40 because the application of power to the machine would otherwise place it beyond the control of the operator.

It will be readily seen that our machine is applicable to an extended variety of abrading-machines—such as grinders, polishers, or lathes—as well as to many other kinds of machines, among which might be mentioned winding and spinning machines.

What we desire to secure by Letters Patent 50 is—

1. In a mechanical movement, a shaft provided with an endless spiral track and a longitudinal track, means for rotating said shaft, a block, a guide for said block, a pin mounted 55 in said block and guided by said endless spiral track, and a rotative member engaged by said block and by said longitudinal track.

2. In a mechanical movement, a shaft provided with an endless spiral track and a longitudinal track, means for rotating said shaft, a block, a guide for said block, a pin in said block projecting into and guided by said endless spiral track, a gear housed in said block engaged by said longitudinal track, a shaft 60 mounted in said block at an angle to the line

of motion thereof, and a rotative member thereon engaged by the gear housed in said block.

3. In a mechanical movement, a frame, a shaft journaled in said frame provided with an endless spiral track and a longitudinal track, means for rotating said shaft, a block mounted on said shaft, a guide for said block, a pin in said block guided by said endless spiral track, means for adjusting said pin, a gear housed 75 in said block, mounted on said shaft and engaged by said longitudinal track, a shaft mounted in said block at an angle to the line of motion thereof, and a rotative member mounted thereon engaged by the gear housed 80 in said block.

4. In a mechanical movement, a frame, a shaft journaled in said frame provided with endless spiral tracks and a longitudinal track, means for rotating said shaft, blocks mounted 85 on said shaft, a guide for said blocks, pins in said blocks engaged and guided by said endless spiral tracks whereby said blocks receive opposite reciprocatory motion relative to each other, gears housed in said blocks, mounted on said shaft and engaged by said longitudinal track, shafts mounted in said blocks at an angle to their line of motion, and rotative members mounted thereon engaged by the gears housed in said blocks. 95

5. In a mechanical movement, a frame, a shaft journaled in said frame provided with an endless spiral track and a longitudinal track, means for rotating said shaft, a block mounted on said shaft, a guide for said block, a pin in 100 said block guided by said endless spiral track, a gear housed in said block, mounted on said shaft and engaged by said longitudinal track, shafts mounted in said block at an angle to its line of motion, and rotative members mounted 105 on said shafts engaged by the gear housed in said block whereby they are rotated in opposite directions relative to each other.

6. In a mechanical movement, a frame, a shaft journaled in said frame provided with 110 endless spiral tracks and a longitudinal track, means for rotating said shaft, blocks mounted on said shaft, a guide for said blocks, pins in said blocks guided by said endless spiral tracks, whereby said blocks receive opposite reciprocatory motion relative to each other, gears housed in said blocks and mounted on said shaft engaged by said longitudinal track, shafts mounted in each of said blocks at an angle to its line of motion, and rotative members 115 mounted on said shafts engaged by the gears housed in said blocks whereby each rotative member is rotated in a direction opposite to that of the other rotative member on the same block.
